COSMETIC CASE

Robert H. Burdge, Kansas City, Mo.

Application March 29, 1937, Serial No. 133,694

10 Claims. (Cl. 132—79)

My invention relates to a case equipped with trays and one object is to provide a case of this character having a suitable number of trays and means for simultaneously adjusting them outwardly to their respective positions where their contents will be readily accessible when the lid of the case, or a certain one of the trays, is opened, or automatically moved back into the case when the lid, or the certain tray, is closed.

10 A further object is to provide the case with a mirror connected in such manner to one of the trays that when the latter is moved outwardly it will automatically place the former in a convenient position for use.

15 For the purpose of illustration I have shown the case equipped with four movable trays, a mirror, and means for actuating said trays and mirror, and in order that the invention may be fully understood reference will now be had to the accompanying drawing, in which:

Fig. 1 is a perspective view of the case with the lid open, the movable trays adjusted outwardly, and the mirror tilted to a position where it may be conveniently used.

20 Fig. 2 is an enlarged section on line 2—2 of Fig. 1.

Figs. 3 and 4 are fragmentary sectional views showing certain parts of the invention.

Fig. 5 is a detail of a part of the mechanism for actuating the movable trays.

Referring in detail to the different parts, 2 designates the main or body portion of the case which has a lid 4 connected thereto by hinges 6. The forward lower portion of the case 2 is provided with a compartment 8 in which a tray or drawer 10 is slidably mounted. The upper portion of the case has a tray 12 connected by hinges 14 to a reinforcement 16 secured to the inner portion of the lid 4.

40 Suitable mechanism is provided for moving the trays 10 and 12 outwardly when the lid 4 is raised (Figs. 1 and 2) and inwardly when the lid 4 is closed. For example, I have shown, in the present instance, such mechanism in the form of a pair of connecting-rods 18 and a pair of levers 20. The connecting-rods 18 are pivoted at their ends to the tray 10 and the levers 20, respectively. The levers 20 are mounted intermediate their ends upon pivots 22 secured to a pair of partitions 24 spaced to provide compartments 26 at the ends of the case 2. The levers 20 extend upwardly at an angle through respective slots 28 in the top 30 of the case 2 and are pivoted at their upper ends to the tray 12.

55 In addition to the trays 10 and 12 and their

actuating mechanism my invention contemplates the use of other trays and means for opening and closing them simultaneously with the opening and closing of said trays 10 and 12, as will hereinafter appear.

Each connecting-rod 18 is equipped near its rear end with a hinge 32, or its equivalent, one leaf of which is connected by a pivot 34 to the respective connecting-rod. The other leaf of each spring 32 has one end of a link 36 pivoted thereto, the opposite end being pivoted to a hinge 38. The hinges 38 are connected to a pair of trays 40 having covers 41 and mounted on hinges 42 secured to the ends of the case 2, so that said trays 40 may be swung into the respective compartments 26, or swung outward to the positions shown by Fig. 1.

44 designates a mirror having a flexible connection 46 at one end secured to the inner surface of the lid 4, and connected at its opposite end to a foldable member 48 secured to a cover 50, having a flexible portion 52 connected to the rear side of the tray 12.

In addition to the trays and compartments above described, the case 2 may be equipped with other suitable trays and compartments. In the present instance I have shown a compartment 54 in the upper forward portion of the case and a removable tray 56 in the rear of said compartment 54.

In practice when the lid 4 is opened it lifts the tray 12 from the dotted line to the full line position, Fig. 2, thereby causing the levers 20 to swing on their pivots 22 and advance the connecting-rods 18 which in turn push the drawer 10 outwardly. As the connecting-rods 18 advance they actuate the links 36 which in turn swing the trays 40 outwardly to the position shown by Fig. 1.

Conversely, when the lid 4 is closed it carries the tray 12 downwardly to the top 30 of the case 2. As the tray 12 descends it swings the levers 20 to the dotted line position, Fig. 2, so that they in turn will move the trays 10 and 40 inwardly through the intermediary of the connecting-rods 18 and the links 36. It is obvious that the lid 4 may be opened or closed and the trays 12 and 40 may be swung outwardly or inwardly by grasping the knob of the drawer 10 and opening or closing the same.

When the lid 4 is opened and the tray 12 is raised to the position shown by Fig. 2, the mirror 44 is tilted at a convenient angle for use as shown. When the cover 50 of the tray 12 is raised by hand to the position shown by Fig. 4

to permit access to the contents of the tray 12, the member 48 folds to the position shown and carries the mirror 44 backward against the inner side of the lid 4, in which position the weight 5 of the mirror will hold the cover 50 in open position and thus leave both hands free to remove or place articles in the tray 12.

If the trays 40 are swung to open position while the case 2 is resting upon a table or other 10 support, the respective covers 41 may be lowered to the surface of such support and thus relieve the hinges 42 of a portion of the weight of said trays and their contents.

Should a more modest type of case be desired 15 the trays 40 and the links 36 may be dispensed with, or the tray 12, the levers 20 and the mirror 44 can be left off. In the latter instance guides 42', or their equivalents, are provided to support the rear ends of levers 20 so that they will 20 actuate the links 36 without binding.

From the foregoing description it will be understood that I have provided an attractive, compact and serviceable case whereby all of the trays excepting tray 56 may be simultaneously positioned 25 by the opening of the lid 4, where their contents are readily accessible and whereby the mirror 44 is positioned at a convenient angle for use. Furthermore, it is to be understood that the case herein shown and described and the operations 30 set forth are subject to such modifications as properly fall within the spirit and scope of the invention as claimed.

Having thus described my invention, what I claim and desire to secure by Letters Patent, is:

35 1. A case comprising a body, a lid hinged to said body, a drawer slidably mounted in the front part of the body, and means adapted to open and close said drawer simultaneously with the lid comprising a tray hinged to the inside of the lid, a pair of levers fulcrumed in the body and operably connected to said tray, and a pair of connecting-rods operably secured to the drawer and the respective levers.

40 2. A case comprising a body, a lid hinged to said body, a drawer slidably mounted in the front part of the body, trays hinged to open and close at the respective ends of the body, and means adapted to open and close the drawer and said trays simultaneously with the lid comprising a tray hinged to the inside of the lid, a pair of levers fulcrumed in the body and operably connected to the last-mentioned tray, a pair of connecting-rods operably secured to the drawer and the respective levers, and links operably secured to said connecting-rods and the trays at the respective ends of the body.

45 3. A case comprising a body, a lid hinged to said body, a drawer slidably mounted in the front part of the body, trays hinged to open and close at the respective ends of the body, covers to said trays adapted to assist in supporting the latter when in open position, and means adapted to open and close the drawer and said trays simul-

taneously with the lid comprising a tray hinged to the inside of the lid, a pair of levers fulcrumed in the body and operably connected to the last-mentioned tray, a pair of connecting-rods operably secured to the drawer and the respective levers, and links operably secured to said connecting-rods and the trays at the respective ends of the body.

4. A case comprising a body, a lid hinged to said body, a tray hinged to the inside of the lid, a cover independent of the lid and operably connected to said tray, and a mirror operably connected to said cover and the inside of the lid in such manner as to be positioned for use by the cover and the lid when the latter is opened and 10 folded downwardly over the tray when the lid is closed.

5. A case comprising a body, a lid hinged to said body, a tray hinged to the inside of the lid, a cover operably connected to said tray, a mirror 20 operably connected at one end to the inner forward portion of the lid, and foldable means operably connecting the opposite end of said mirror to the cover in advance of the latter's connection to the tray so that when said cover is opened it will 25 be retained in such position by the weight of the mirror.

6. A case comprising a body, a drawer arranged to slide in a straight line in said body, a tray arranged to move in and out of one end of said body at right angles to the movement of the drawer, and means operably connecting said tray to the drawer whereby when the latter is opened or closed the former will operate in unison therewith.

7. A case comprising a body, a drawer slidably mounted in said body, a tray arranged to move in and out of one end of said body, and means whereby the tray is operated in unison with the drawer comprising a rod operably connected to 40 said drawer, and a link operably connected to the rod and said tray.

8. A case comprising a body, a drawer slidably mounted in said body, trays arranged to move in and out of the respective ends of the body, and means operably connecting said trays to the drawer whereby when the latter is opened or closed the former will operate in unison therewith.

9. A case comprising a body, a drawer slidably mounted in said body, trays arranged to move in and out of the respective ends of the body, and means whereby the trays are operated in unison with the drawer comprising a pair of rods connected to the drawer, and links operably connected to said rods and the respective trays.

10. A case comprising a body, a tray mounted to move in and out of one end of said body, and a cover to said tray adapted to be swung downward to open position to assist in supporting the tray after the same has been moved out of the body.

ROBERT H. BURDGE.
